(57) **CLAIM**

We claim the ornamental design for the lighting for pallet truck, as shown and described.

DESCRIPTION

FIG. 1 is a left, front isometric view of a first lighting configuration for a pallet truck;

FIG. 2 is a front view of the pallet truck of FIG. 1;

FIG. 3 is a top view of the pallet truck of FIG. 1; and
FIG. 4 is a right side view of the pallet truck of FIG. 1, the
left side view being a mirror image of the right side view.
FIG. 5 is a left, front isometric view of a second lighting
configuration for a pallet truck;

FIG. 6 is a front view of the pallet truck of FIG. 5;

FIG. 7 is a top view of the pallet truck of FIG. 5; and
FIG. 8 is a right side view of the pallet truck of FIG. 5, the
left side view being a mirror image of the right side view.
FIG. 9 is a left, front isometric view of a third lighting
configuration for a pallet truck;

FIG. 10 is a front view of the pallet truck of FIG. 9;

FIG. 11 is a top view of the pallet truck of FIG. 9; and
FIG. 12 is a right side view of the pallet truck of FIG. 9, the
left side view being a mirror image of the right side view.
FIG. 13 is a left, front isometric view of a fourth lighting
configuration for a pallet truck;

FIG. 14 is a front view of the pallet truck of FIG. 13;

FIG. 15 is a top view of the pallet truck of FIG. 13; and
FIG. 16 is a right side view of the pallet truck of FIG. 13,
the left side view being a mirror image of the right side view.
In FIGS. 1-16, the broken lines indicate environmental
features and form no part of the claimed design.
